DETECTION OF LEAKS IN HYDROCARBON STORAGE SYSTEMS

Patrick F. Dougherty, Chester Heights, Pa., assignor to Sun Oil Company, Philadelphia, Pa., a corporation of New Jersey

Application March 19, 1954, Serial No. 417,433

3 Claims. (Cl. 73—40.5)

This invention relates to a method for detecting leaks in tubing employed in the sub-surface storage of hydrocarbons, and more particularly relates to a method for detecting and locating leaks in tubing employed for introducing and removing brine from sub-surface salt cavities in processes for storing hydrocarbons in such cavities.

The storage of hydrocarbons, such as propane, in sub-surface salt cavities is well-established. Such cavities are usually prepared by drilling to a point within a sub-surface salt formation, such as a salt stratum or salt dome, and dissolving salt therefrom by contacting with water circulated into the well, brine being removed from the system as water is introduced. Circulation of water and removal of brine is continued until a cavity of the desired capacity is obtained. A tubing, which can be the tubing employed for introducing water in the preparation of the cavity, is positioned within the borehole and provides fluid communication between the lower portion of the cavity and the ground surface. The usual method of storing hydrocarbons in the cavity is to introduce the hydrocarbon to be stored through the annulus between the borehole wall, or borehole casing, and the tubing positioned within the borehole. For brevity, this annulus, which provides fluid communication between the ground surface and the upper portion of the salt cavity, is hereinafter designated simply as the "annulus," or "borehole annulus." The introduced hydrocarbon forms an upper layer over brine and as hydrocarbon is introduced, brine is displaced from the system through the tubing. The stored hydrocarbon is recovered by introducing brine through the tubing, thereby forcing hydrocarbons to the surface through the annulus. In operating the process for hydrocarbon storage, brine is always maintained in the tubing regardless of whether hydrocarbon is being introduced, removed, or remaining in storage.

The presence of leak in the tubing creates an extremely hazardous condition. For example, in the initial filling of a salt cavity with a hydrocarbon by introducing the hydrocarbon into the cavity through the annulus, the presence of a leak in the tubing results in introduced hydrocarbon flowing through the leak and out of the system through the tubing in which brine alone normally flows. An extremely hazardous condition results from the escape of quantities of propane, which in any event is lost to the operator. Leaks which cause such a dangerous condition can be initiated as cracks or pin holes present in the drill pipe which are enlarged by circulation of brine in the preparation of the cavity, or in subsequent movement of brine through the tubing in the storage of hydrocarbons. Leaks can also be through threaded connections between sections of tubing, or through ruptures in the tubing caused by a portion of the borehole wall collapsing.

In the rotary drilling of wells employing continuous circulation of fluid, such as drilling mud, methods for determining leaks in the drilling stem have been described. These methods are usually based upon continuous circulation of a fluid such as drilling mud, and/or employ delicate pressure measurements, and/or introduce foreign

2

materials into the system, and hence are not suitable for testing tubing in the present instance.

An object of the invention is to provide a process for determining leaks in tubing employed as the brine conduit between the cavity and ground surface in the sub-surface storage of hydrocarbons. A further object is to determine the location of leaks in such tubing. Other objects will be apparent from the following specification.

It has now been found that by filling with brine the system used in the sub-surface storage of hydrocarbons, which system comprises the salt cavity, tubing and annulus, and thereafter introducing a quantity of propane into the tubing thereby displacing a quantity of brine through the annulus, discontinuing the introduction of propane for a time sufficient to permit any propane passing by leakage from the tubing to the annulus to reach the surface of the brine in the annulus, and testing for the presence of propane in the upper portion of the annulus, the presence or absence of a leak in the portion of the tubing filled with propane is established. A further quantity of propane is then introduced and the above steps repeated. The existence of propane in the annulus indicates a leak, and from a knowledge of the size of the tubing and the volume occupied by propane introduced, the location of the leak can be readily ascertained. By introducing relatively small increments of propane, the location of the leak can be ascertained with considerable accuracy. Where only a rough determination of the location of the leak is desired, a relatively large quantity of propane can be introduced to fill a relatively large section of the tubing which, of course, gives a more rapid but less accurate method for determining the location of a leak. The volume occupied by the propane, which determines the level thereof in the tubing, is determined by measuring the volume introduced, or by measuring the volume of brine displaced thereby.

The accompanying figure is a more or less diagrammatic illustration of an assembly for performing the method of the invention and is hereinafter discussed in detail.

To illustrate the process of the invention, a sub-surface salt cavity of about 50,000 barrels capacity designed for storing hydrocarbons is filled with brine. The annulus providing fluid communication between the ground surface to the upper portion of the cavity and the tubing providing fluid communication between the ground surface and the bottom portion of the cavity are also filled with brine. A measured volume of liquid propane is then introduced into the tubing and an equivalent volume of brine is thereby displaced from the system through the annulus. The upper portion of the annulus is tested for propane. If the test is negative an additional measured volume of propane is introduced into the tubing and the steps of testing for propane repeated. The detection of propane in the annulus after the introduction of any given increment of propane locates the leak within that portion of tubing from which brine was displaced by such increment.

Propane has been used in the foregoing description of the invention for convenience. Other hydrocarbons may be employed and it is advantageous to employ in the test the hydrocarbon to be stored. Good results are obtained, for example, with butane, pentane, hexane, hydrocarbon mixtures such as gasoline, and the like. It is preferred to employ a hydrocarbon, or mixture of hydrocarbons, which can be introduced and maintained as a liquid within the tubing, but which on reaching the upper portion of the annulus, which is maintained substantially at atmospheric pressure, becomes a gas. Propane and butane are the preferred hydrocarbons to employ. It may be observed that in maintaining a hydrocarbon such as propane in the liquid phase within the tubing, especially during the initial stages of operation, it is desirable to

introduce the propane at a pressure regulated with respect to the rate brine is displaced from the system so that the pressure maintains the propane in liquid phase. The time required to permit any propane that may escape into the annulus to rise to the upper portion thereof is insufficient for the propane to become gaseous. In the event normally liquid hydrocarbons are used, such as gasoline, instead of testing the upper portion of the annulus for gas, it is tested by any convenient appropriate means for the liquid hydrocarbon or hydrocarbon mixture used. Hydrocarbons that remain gaseous when employed in the process, such as ethane, methane, and mixtures thereof and the like, can also be employed but are not preferred. When such gaseous hydrocarbons are employed, it is advantageous to measure the quantity of the effluent brine displaced to determine the location of the gas-brine interface within the tubing rather than by measuring the volume of gas introduced. When the quantity of effluent brine is measured, it is advantageous to operate the process with substantially saturated brine so that contraction of liquid volume, observed on increasing the salt concentration in brine, is not a factor. In any event, however, the contraction is small in relation to the volume of brine displaced and can be ignored in most operations.

Various methods can be employed for detecting the hydrocarbon which, in the event of a leak, appears in the upper portion of the annulus during the present process. Conventional type gas detectors give good results where the hydrocarbon is a gas under the conditions, which may include substantially atmospheric pressure, existing in the upper portion of the annulus. For example, a gas trap of a type known to the art can be employed and has the advantage, in some methods, of providing for the visual determination of the presence of gas.

Attention is now directed to the accompanying figure which is a more or less diagrammatic illustration of the process of the invention. Salt cavity 1, located in sub-surface salt formation 2, is provided with fluid communication with the ground surface through tubing 4 and annulus 5, which is the annulus between borehole casing 7 and tubing 4. In the process of storing hydrocarbons, the hydrocarbon to be stored is introduced through conduit 6 and passes through annulus 5 into cavity 1, and in so doing displaces brine from the system through tubing 4. The hydrocarbon, being of lower specific gravity than, and substantially immiscible with, the brine, forms an upper layer over the brine layer. For recovery of the hydrocarbon, the flow is reversed, brine being introduced through tubing 4 to displace stored hydrocarbon annulus 5 and conduit 6.

In testing for leaks in tubing 4 in accordance with the invention, the entire system is filled with brine. It is advantageous to make this test before using the cavity for hydrocarbon storage, since the system is at that time filled with brine from the preparation of the cavity. The process may, however, be employed at any time necessary or desirable. It is preferred to use brine substantially saturated with respect to salt. In the event the brine is not saturated, it can be circulated through the cavity until substantial saturation is reached. Propane, used to illustrate various materials which can be employed in liquid phase, is introduced into tubing 4 to a level represented by 8. The rate of introduction is such that the propane is maintained in liquid phase. The location of level 8 is determined by measuring the volume of propane introduced, or by measuring the volume of brine effluent from conduit 6. For most applications, compressibility of the liquid propane, or other liquid hydrocarbon, can be ignored. A time sufficient for any propane escaping from tubing 4 to annulus 5 to pass upwardly to the top of annulus 5 is allowed. The actual time required for propane escaping from the tubing to rise to the top of the annulus depends upon the depth of the leak, the difference in specific gravity of the brine and propane, and

the like, but will seldom be more than several minutes, and will under all practical conditions of operation be substantially within the range of from about 1 second to 10 minutes. The specific gravity of the brine can vary 5 from about 1.003 to about 1.2, but will usually be from about 1.1 to 1.2, saturated brine having a specific gravity of about 1.2 under usual conditions of operation. The top portion of the annulus or equivalent portion of the system is then tested for propane. If none is found, an 10 additional increment of propane is introduced through tubing 4, say to a level represented by 9, and the foregoing steps repeated. In the figure used to illustrate the invention, any propane escaping through tubing 4 passes up through annulus 5 and is thereafter detected. It is preferred to employ a gas trap such as represented by 10, it being understood that the gas trap can be connected with conduit 6 preferably adjacent borehole casing 7, or the like. Propane can be removed from trap 10 through conduit 12 by operating valve 11, and the presence thereof 15 in conduit 12 can be established by any convenient means. It is advantageous in some instances to have at least a portion of gas trap 10 or its equivalent constructed of transparent material so that visual observation of gas therein can be made. This can be accomplished by 20 having the entire trap 10, or a portion thereof, made of transparent material, such as glass or a transparent plastic, or by providing a sight glass (not shown) by conventional means. Where conduit 6 is at substantially the upper end of the annulus, the effluent brine can be tested for 25 propane and good results obtained. The steps of introducing propane and testing for leaks can be repeated until the entire length of tubing 4 is tested. Any suspected portion thereof can likewise be tested. An advantage of 30 the present invention is that small increments of propane can be introduced in order to determine within relatively narrow limits the location of a leak. For example, if a large increment of propane locates a leak between levels 35 8 and 9, brine can be introduced through conduit 6 and annulus 5 to force propane out through tubing 4 until 40 the level of the brine is above height 8. Propane is then introduced in relatively small increments until the leak, known to be between heights 8 and 9, is precisely determined.

In some instances, a tubing such as represented in 45 the figure by numeral 4 is broken or damaged within the cavity such as by a falling stringer. By "stringer," as used herein, is meant a relatively narrow vein of substantially water insoluble material that remains suspended from the top or side of the cavity after salt is dissolved 50 from around it. Such damage or breakage is determined in the process of the invention, and hence can be corrected prior to the introduction of large quantities of propane through the annulus.

Pumps, valves, gauges, and the like, the location and 55 use of which are within the scope of those skilled in the art, have been largely omitted from the figure.

Example

60 A salt cavity at a sub-surface depth of about 2300 feet having a capacity of about 50,000 barrels was prepared as above described. Before introducing propane for storage therein, it was desired to test for leaks the tubing to be used as the brine conduit in the storage process.

65 With the system, including the cavity, annulus and tubing filled with substantially saturated brine having a specific gravity of about 1.2, a measured volume of liquid propane, about 2 barrels, was introduced into the tubing. The tubing had an internal diameter of 4 $\frac{1}{4}$ inches, and hence the propane-brine interface in the tubing was 70 lowered about 40.7 feet by each barrel of propane added. A time sufficient for propane to appear in the upper portion of the annulus, about 5 seconds, was permitted and the upper portion of the annulus tested for propane. The test was negative. Additional measured increments of 75 liquid propane were introduced and the above procedure

repeated, the measured increments of propane varying from about 1 to 3 barrels. A total of about 54 barrels of liquid propane, introduced in increments of from 1 to 3 barrels, completed the test. The time allowed for propane to rise to the upper portion of the annulus on introduction of the last increment of liquid propane was about 10 minutes. In the actual test no leak was found, and hence the cavity was immediately placed in service for the storage of hydrocarbons by introducing brine into the annulus to force the propane from the tubing, and then introducing propane into the annulus for storage over brine as hereinbefore described. No difficulty from leaks was observed in the subsequent storage of propane.

The invention claimed is:

1. In the method of storing a hydrocarbon in a sub-surface salt cavity having fluid communication with the ground surface through a tubing positioned within the borehole and through the borehole annulus, said borehole annulus providing fluid communication between the ground surface and the upper portion of said cavity and said tubing providing fluid communication between the ground surface and the lower portion of said cavity, in which method the hydrocarbon to be stored is introduced into said cavity through said annulus to thereby displace brine from the system through said tubing, and in which method the stored hydrocarbon is recovered by introducing brine into said cavity through said tubing to thereby displace stored hydrocarbon from the system through said annulus, the method of detecting and locating leaks in said tubing which comprises the steps of: (1) filling said cavity, said annulus and said tubing with brine, (2) introducing a quantity of hydrocarbon into said tubing sufficient to displace a portion of the brine therefrom and from the system through said annulus, (3) discontinuing the introduction of hydrocarbon for a time sufficient to allow hydrocarbon passing from a leak in said tubing to said annulus to rise to the upper end of said annulus, (4) testing for hydrocarbon at the upper end of said annulus, (5) repeating said steps (2), (3) and (4) until at least a portion of said tubing has been tested, whereby the existence and location of a leak in said tubing is determined.

2. Method according to claim 1 wherein the hydrocarbon introduced into tubing is a normally liquid hydrocarbon.

3. In the method of storing a hydrocarbon in a sub-surface salt cavity having fluid communication with the ground surface through a tubing positioned within the borehole and through the borehole annulus, said borehole annulus providing fluid communication between the ground surface and the upper portion of said cavity and said tubing providing fluid communication between the ground surface and the lower portion of said cavity, in which method the hydrocarbon to be stored is introduced into said cavity through said annulus to thereby displace brine from the system through said tubing, and in which method the stored hydrocarbon is recovered by introducing brine into said cavity through said tubing to thereby displace stored hydrocarbon from the system through said annulus, the method of detecting and locating leaks in said tubing which comprises the steps of: (1) filling said cavity, said annulus and said tubing with brine, (2) introducing a known volume of propane into said tubing sufficient to thereby displace a portion of the brine therefrom and from the system through said annulus, (3) discontinuing the introduction of propane for a time sufficient to allow propane passing from a leak in said tubing to said annulus to rise to the upper end of said annulus, (4) testing for propane at the upper end of said annulus, (5) repeating said steps (2), (3) and (4) until at least a portion of said tubing has been tested, whereby the existence and location of a leak in said tubing is determined.
